C. KNOWLES.

WATER CONTROL SYSTEM FOR SURFACE GRINDERS,

APPLICATION FILED NOV. 9, 1920.

1,416,475.

Patented May 16, 1922.

UNITED STATES PATENT OFFICE.

CARROLL KNOWLES, OF HARTFORD, CONNECTICUT, ASSIGNOR TO PRATT & WHITNEY COMPANY, OF NEW YORK, N. Y., A CORPORATION OF NEW JERSEY.

WATER-CONTROL SYSTEM FOR SURFACE GRINDERS.

1,416,475.

Specification of Letters Patent. Patented May 16, 1922.

Application filed November 9, 1920. Serial No. 422,901.

To all whom it may concern:

Be it known that I, CARROLL KNOWLES, a citizen of the United States, residing at Hartford, in the county of Hartford and 5 State of Connecticut, have invented certain new and useful Improvements in a Water- Control System for Surface Grinders, of which the following is a specification.

This invention relates to grinding machines of the surface type in which a wheel 10 of abrasive material is rapidly revolved, preferably about a vertical axis, and brought down into contact with work to be ground mounted upon a slowly revolving 15 table.

It is an object of the present invention to provide a supply of water to the contacting surface of an abrasive wheel and work mounted on a revolving table, and particularly 20 to provide means for conveniently controlling the amount of water supplied. These controlling means operate to supply a quantity of water only when the wheel 25 is in engagement with the work and act automatically to cut off the supply of water when the wheel is raised out of engagement with the work.

A further object of the invention is to provide means to vary the amount of water 30 supplied to the wheel and work during the grinding operation and to admit or cut off this variable amount of water when the wheel is in or out of contact with the work.

A further object of the invention is to 35 provide a main controlling valve for the water supply, this valve being adapted to be opened variable distances when the wheel is in engagement with the work and tightly or partly closed when the wheel is raised 40 out of engagement with the work.

This application forms a continuation in part of my copending application Serial No. 389,431, filed June 16, 1920.

In the accompanying drawings I have 45 shown an embodiment of the invention which I now deem preferable but it is to be understood that changes and modifications may be made within the scope of the appended claims without departing from the 50 spirit of the invention.

In the drawing:

Figure 1 shows a side view of a machine to which the present invention has been applied.

Fig. 2 shows, on an enlarged scale, parts 55 forming the water controlling device.

Fig. 3 shows a side view thereof, and

Fig. 4 shows a plan view of the same.

The invention in its broadest aspect comprises the following principal elements; 60 namely, first, a surface grinding machine which may be of the type disclosed in my copending application above mentioned; second, a water supply system adapted to convey water or other cooling fluid from a 65 suitable pump to work mounted on a rotating table; third, a valve for regulating the supply of water to the above mentioned part; and fourth, a device operated by a 70 wheel elevating lever to open and close this valve simultaneously with movement of the lever to raise or lower the wheel.

Referring more particularly to the figures of the drawings in which is shown a machine provided with the present invention, 75 10 refers to the base or frame of the surface grinding machine which is provided with a column 11 resting upon the upper surface of the base 10. Preferably the column 11 is rigidly secured to the base 10, the securing 80 means holding the column permanently in position perpendicularly to the upper surface of the base. The forward vertical surface of column 11 is provided with vertical ways 12 by means of which a wheel 85 slide 13 is accurately guided in its movement toward and away from the work table 14 and held in sliding engagement with the column 11.

The wheel slide 13, the column 11 and 90 the table 14 as well as the driving means for the wheel and table are in every way similar to the corresponding devices shown in my copending application above referred to and further description of these parts is 95 therefore thought to be unnecessary.

As is usual in this class of machines, the wheel 15 and the work mounted on table 14 are flooded with water to prevent them from becoming overheated. This water 100 may be supplied through conduits to be described in detail later to a position 16 adjacent the table 14 outside the abrasive wheel 15 and also, as shown at 17, to a point adjacent the table 14 within the abrad- 105 ing ring of the wheel 15. Fig. 1 shows means for supplying water to both of these positions or nozzles 16 and 17, one of which

positions may be used alone, or both may be used simultaneously.

At 19 is shown a conduit extending from a pump 20 preferably mounted at one side 5 of the machine and adapted to be supplied with water by conduit 21 from a suitable tank preferably formed by the cavity within the base 10 of the machine. In conduit 19 is inserted a controlling valve 22 10 from which valve the conduit 19 extends to the position 17 just in rear of the table and below the wheel slide.

As shown in Fig. 1, the position 17 of the orifice of the conduit 19 is within the periphery of the wheel 15 and just in rear of the table 14 so that water may be supplied to the point 17 from which it will be discharged directly onto the work. As the table 14 and wheel 15 are normally used 20 in overlapped positions there is ample space for the conduit 19 to be extended to the point shown.

It is desirable in the operation of these machines that water be supplied to the 25 work being ground and to the wheel 15 at all times during which the grinding operation is being carried out, but, as soon as the grinding is stopped and the operator is ready to test or remove the work from 30 the table 14 the water should be immediately shut off so that the operation of removing or testing the work being ground may be more satisfactorily accomplished.

In order to accomplish this, I provide 35 mechanism coupled to the wheel elevating lever shown at 25 so that as soon as the work has been ground to the desired thickness and the arm or lever 25 raised to disengage the wheel 15 from the work, water 40 is promptly throttled or completely cut off from the position 17 and, as soon as grinding is started again and the wheel elevating lever 25 lowered, water is automatically started again.

45 I therefore extend the stem 28 of the main control valve 22 by means of extension 29 to a point vertically below the wheel operating lever 25 and at that point connect it by means of a bell-crank in a manner presently 50 to be described, to the lever 25.

At one side of the machine column 11 is a bracket member 31 in which a short shaft 32 is mounted carrying a bell-crank 30. Adjacent the bell-crank 30 is another bell-crank 33 which is also pivotally mounted on the shaft 32. A yoke 34^a is provided on one of the arms of the bell-crank 30 adapted to fit around the valve stem extension 29. The other arm of this bell-crank 30 is extended 55 into a handle 34 by means of which the valve stem may be manually operated to open or close the valve 22 if, at any time, it is desired to do so independently of movement of the lever 25. This bell-crank 30 is adapted to 60 be attached to bell-crank 33 by means of a

pin 35 housed in bell-crank 30 and forced outwardly into engagement with a depression within bell-crank 33 by a spring 36. A knob 37 on the end of this pin 35 enables the operator to withdraw it so that one bell-crank may be operated independently of the other. Stop members 40 mounted on bracket member 31 limit the throw of the bell-crank 30 when operated manually by the handle 34. These contact with set screws 41 mounted in the bell-crank 30 and which may be adjusted to limit or vary the movement of this bell-crank and consequently the movement of the valve stem extension 29.

The bell-crank 33 is attached as shown at 45 to a link 46 which, at its upper end, is attached to a part of the wheel elevating lever 25 so that movement of the lever 25 oscillates the bell-crank 33 and through this the other bell-crank 30 to open and close the valve 22.

The link 46 is so connected to the lever 25 that the valve retains its maximum opening for a comparatively long arc of movement of the lever 25. This will be obvious from an inspection of Fig. 1.

In order to adjustably connect the yoke 34^a of bell-crank 30 to the valve stem extension 29, I provide this extension with a threaded end as shown at 47 on which are mounted two collars 48 and 49. The positions of these collars 48 and 49 may be adjusted along the extension 29 so that the distance between them may be varied. By suitably spacing the collars 48 and 49 apart in this manner, the movement of the valve stem 28 and extension 29 may be varied by reason of the varied amount of lost motion between the yoke 34^a and the collar 49. This enables me to limit the opening of valve 22 to any desired part of its full opening or to limit its closing movement.

The collar 48 is set in all cases so that when the lever 25 is in its uppermost position the valve stem 28 will be in position to tightly close the valve 22. Preferably I mount a light spring 50 between the collar 48 and the side of the column 11, this serves to counterbalance the weight of handle 34.

In the operation of this device, as soon as the lever 25 is lowered to the position shown 115 in full lines in Fig. 1, thus bringing the wheel 15 into contact with the work mounted on table 14 and starting the grinding, the valve 22 is opened, thus admitting water to the contacting surfaces of the wheel 15 and the work. This is accomplished in the following manner: movement of the lever 25 downward lowers the link or connecting rod 46 and oscillates the bell-crank 33 about shaft 32. Bell-crank 33 is detachably attached to bell-crank 30 as above described so that the two bell-cranks 30 and 33 oscillate together thus forcing the rod 29 to the right and opening the valve 22. The reverse movement of lever 25 to raise the wheel 15

from the table 14 raises the link 46 thus forcing the extension 29 to the left to close the valve 22.

The position of nozzle 17 may be varied 5 and for that reason a section 19^a of the conduit 19 is made flexible. A portion of the conduit 19 adjacent the nozzle 17 passes through a bracket 55 to which the conduit 19 may be fastened in any adjusted position 10 by a clamping screw 56.

The conduit 19 is preferably provided with a branch as shown at 51 extending to the nozzle 16 forward of the wheel 15. As shown in Fig. 1, this branch 51 separates 15 from conduit 19 before conduit 19 reaches the valve 22. The branch conduit 51 therefore is unaffected by the opening and closing of the valve 22 and so will be provided with a flow of water at all times that the pump 20 20 is in operation. In the branch conduit 51 is provided a valve 52 adjacent the nozzle 16 so that the supply of water through branch 51 may be manually varied or cut off. If desired, however, the branch 51 may separate from conduit 19 at a point beyond the valve 22 in which case the supply of water to nozzle 16 will also be controlled by the opening and closing of the valve 22.

From the above description, it will be seen 30 that movement of the wheel raising lever 25 will open and close the valve 22 and control the supply of water to the work as required. Also if desired, the valve 22 may be controlled manually by handle 34 independently 35 of the lever 25 by removing the pin 35 from engagement with the bell-crank 33.

What I claim is:

1. In a surface grinding machine, the combination of an annular abrasive wheel, a 40 work table mounted in overlapped relation thereto and out of alignment therewith, and a stationary water supply conduit extending to a point adjacent the periphery of said work table and within the periphery of the 45 abrasive wheel.

2. In a surface grinding machine, the combination of an annular abrasive wheel rotatable about a vertical axis, a work table mounted in overlapped relation thereto and 50 out of alignment therewith, and a water supply conduit extending to a point adjacent the periphery of said work table within the periphery of the wheel and within the overlapped portion of the wheel.

3. In a surface grinding machine, the combination of an annular abrasive wheel rotatable about a vertical axis and engaging the work on one of its flat end faces, a work 60 table rotatable about an axis parallel to said wheel axis and out of alignment therewith, and a stationary water supply conduit terminating adjacent said work table and within the periphery of the wheel whereby water 65 may be supplied to the work within the area engaged by the wheel.

4. In a surface grinding machine, the combination of an abrasive wheel, a work table mounted in relation thereto, a stationary water supply conduit extending to a point adjacent said work table and within the periphery of the abrasive wheel, and means 70 permitting adjustment of said water supply conduit.

5. In a surface grinding machine, the combination of an annular abrasive wheel 75 rotatable about a vertical axis, a work table mounted in overlapped relation thereto, a water supply conduit extending to a point adjacent said work table and within the overlapped portion of the wheel, and means 80 permitting vertical adjustment of said water supply conduit.

6. In a surface grinding machine, the combination of an annular abrasive wheel rotatable about a vertical axis and engaging the 85 work on one of its flat end faces, a work table mounted in overlapped relation thereto, a water supply conduit extending to a point adjacent said work table and within the overlapped portion of the wheel, and means 90 permitting adjustment of said water supply conduit.

7. In a surface grinding machine, the combination of an annular abrasive wheel rotatable about a vertical axis and engaging the 95 work on one of its flat end faces, a work table rotatable about an axis parallel to said wheel axis, a stationary water supply conduit terminating adjacent said work table and within the periphery of the wheel 100 whereby water may be supplied to the work within the area engaged by the wheel, and means permitting adjustment of said conduit relative to said work table and wheel.

8. In a surface grinding machine, the combination of a grinding wheel, a work holding table, means to supply water to said wheel and table, a valve to control said supply, means operated by movement of said wheel toward and away from said table to open 110 and close said valve, said means comprising a lever, a bell-crank, and a valve stem, said valve stem being attached by means of said lever and bell-crank to said wheel elevating means.

9. In a surface grinding machine, the combination of a grinding wheel, a work holding table, means to supply water to said wheel and table, a valve to control said supply, means operated by movement of said wheel toward and away from said table to open 120 and close said valve, and a detachable connection between said means and valve whereby said valve may be manually operated or operated by movement of said wheel 125 toward or from said table.

10. In a surface grinding machine, the combination of a grinding wheel, a work holding table, means to supply water to said wheel and table, a valve to control said sup- 130

ply, means to raise and lower said wheel, means connected to said raising and lowering means and operated thereby to open and close said valve, and an adjustable connection between said raising and lowering means and said valve to vary the amount of opening of said valve.

11. In a surface grinding machine, the combination of a grinding wheel, a work holding table, means to supply water to said wheel and table, a valve to control said supply, a valve stem therefor, a lever to raise and lower said wheel, means connected to said raising and lowering means and operated thereby to open and close said valve, and an adjustable connection between said raising and lowering means and said valve stem to limit the opening of said valve.

12. In a surface grinding machine, the combination of a grinding wheel, a work holding table, means to supply water to said wheel and table, a valve to control said supply, a valve stem therefor, means to raise and lower said wheel, means connected to said raising and lowering means and operated thereby to open and close said valve, and an adjustable connection between said valve and said raising and lowering means, comprising a pair of spaced collars on said valve stem to limit the opening of said valve.

13. In a surface grinding machine, the combination of a grinding wheel, a work holding table, means to supply water to said wheel and table, a valve to control said supply, means to raise and lower said wheel, a link attached to said raising and lowering

means, a bell-crank operated by movement of said link, a second bell-crank connected to said first bell-crank to open and close said valve, and means connecting said second bell-crank with said valve to open and close it simultaneously with movement of said wheel toward and away from said table.

14. In a surface grinding machine, the combination of a grinding wheel, a work holding table, means to supply water to said wheel and table, a valve to control said supply, means to raise and lower said wheel, a link attached to said raising and lowering means, a bell-crank operated by movement of said link, a second bell-crank connected to said first bell-crank, and means to detachably connect said bell-cranks to operate simultaneously, said second bell-crank being connected to said valve to open and close it simultaneously with movement of said wheel toward and from said table.

15. In a surface grinding machine, the combination of a grinding wheel, a work holding table, means to supply water to said wheel and table, a valve to control said supply, a valve stem therefor, means to raise and lower said wheel, a link attached to said raising and lowering means, and a bell-crank operated by movement of said link, and spaced collars connecting said valve stem to said bell-crank to open and close said valve simultaneously with movement of said wheel toward and away from said table.

In testimony whereof, I hereto affix my signature.

CARROLL KNOWLES.
